MUFFLER

John C. Walker, Jackson, Mich., assignor to Walker
Manufacturing Company, Racine, Wis., a corporation
of Delaware

Filed June 12, 1963, Ser. No. 75,330

Term of patent 3½ years

(Cl. D14—6)

Fig.1.

Fig.2.

Fig.3.

FIGURE 1 is a perspective view of a muffler showing my new design;

FIGURE 2 is a side elevational view thereof; and

FIGURE 3 is a side elevational view of FIGURE 2 rotated 45 degrees.

The characteristic features of the design reside in the spaced dimple-like depressions and intermediate cushion-like surfaces.

I claim:

The ornamental design for a muffler, as shown and described.
